MAGNETIC SWITCH

Joseph H. Pengilly, Rupert P. Snone, and Lawrence G. Maechtlen, Los Angeles, Calif., assignors to Square D Company, Inc., a corporation of Delaware

Application April 24, 1929, Serial No. 357,672

6 Claims. (CL 200—5)

Our invention relates to electrical switches, and more particularly to those switches which are operated by a magnetic means which is controlled by a control switch. Such control switches are usually situated some distance from the magnetic switch itself, thus requiring unnecessary wiring and a separate container therefor.

It is an object of our invention to provide a magnetic switch controlled by a control switch situated in the same enclosing structure as the magnetic switch, this control switch being operable from the exterior of the enclosing structure without danger of manual contact with any of the working parts of the switch.

15 A further object of the invention is to provide a magnetic switch and a control switch therefor, both mounted on the same panel, and to provide an opening in the enclosing structure through which an arm capable of operating the control switch may extend when the enclosing structure is closed. Such an arrangement permits easy access to the terminals and working parts of the switch when the switch is dead and when the enclosing structure is open, and eliminates any 20 flexible leads connecting the control switch contacts with the main switch contact.

25 A further object of the invention is to provide a magnetic switch controlled by a single control member, which if moved in one direction, causes the switch to close, and if moved in another direction opens the switch.

Still a further object of the invention is to provide a relay which may be reset by a movement of such a control member.

30 A further object of this invention is to provide a contactor bar carrying one or more contacts and moved under the influence of an electromagnet during the closing of the switch, this contactor bar being so mounted as to utilize gravitational forces during the opening of the switch.

35 A further object of the invention is to provide an enclosing structure for a switch in which a wiring space is provided in the rear of the switch panel so that all conduits may communicate with this space. Such a construction allows wires to be brought in from any side of the enclosing structure through suitable knock-outs provided therein, and allows all of the external wires to lie in this wiring space, thus preventing these wires 40 from passing in front of the operating mechanism or being otherwise in danger of entanglement therewith.

45 A further object of the invention is to mount an electromagnet solenoid in an opening of the switch panel, preferably so that the electromag-

net extends into the wiring space. Such a construction permits a definite saving in space and allows the pivot point about which the contactor bar moves to be so positioned that this contactor bar, and the armature associated therewith, may be moved gravitationally without the use of any linkage.

5 Still a further object of the invention is to provide a contactor bar with a plurality of shields formed integrally therewith, each adjacent pair of shields defining a channel in which a contact may be moved.

10 Still other objects lie in the particular structure of the contactor mounting. In the mounting of our invention, the contactors are easily and quickly removable for inspection or replacement, and are resiliently retained against corresponding contacts by a spring. In our construction this spring is not obliged to carry any electrical current, thus preventing any annealing thereof due 15 to the heat generated therein by the passage of electrical current therethrough.

15 Another object of the invention is to provide contacts which are pivoted to the contacting bar and which have a very desirable wiping action 20 during the closing and opening of the switch.

25 Another object of the invention is to provide a switch having easily removable arc shields for preventing any arcing between the contacts connected to contactors of different potential.

30 Another object of the invention lies in the novel pivot support for the armature which carries the contactors and a contactor bar.

35 Still another, and very important, object of the invention is to provide a switch which may be utilized for a number of different purposes including both the magnetic and manual control of electrical appliances.

40 Further objects and advantages of this invention will be made evident in the following description. This is especially true with regard to the particular construction of the switch which we have found to be not only a very efficient one, but also one permitting manufacturing economies not heretofore attained.

45 Referring to the drawings, in which we have shown a preferred embodiment of our invention for illustration,—

Fig. 1 is a perspective view of our switch unit with one of the arc shields removed.

50 Fig. 2 is a front view of the switch with the cover of the enclosing structure closed.

Fig. 3 is a front view of the switch with the enclosing structure open.

55 Fig. 4 is a detailed sectional view of the main

switch elements of our invention, and is taken as indicated by line 4—4 of Fig. 3.

Fig. 5 is another detail of this construction taken on the line 5—5 of Fig. 3.

5 Fig. 6 is a view of the key of our invention.

Fig. 7 is a vertical sectional view taken on the line 7—7 of Fig. 3.

10 Figs. 8, 9, and 10 are sectional views of the control switch of our invention in three different positions, these, however, being taken as indicated by the line 8—8 of Fig. 3.

Fig. 11 is a detailed side view of the magnetic system of our invention.

15 Fig. 12 is a view taken on the line 12—12 of Fig. 11.

Fig. 13 is a diagrammatic view illustrating the adjustable pivoting means utilized in our magnetic system.

20 Fig. 14 illustrates the wiring diagram of our switch.

Fig. 15 is a view similar to Figs. 8, 9, and 10 and illustrates an attachment which may be utilized to adapt the switch of our invention for use with any pilot control, such as float switches, 25 pressure governors, thermostats, etc.

Fig. 16 is a wiring diagram of the form of our switch shown in Fig. 15.

Referring particularly to Figs. 2, 3, and 7, the switch of our invention is enclosed in an enclosing 30 structure 15 formed of a box 16 and a cover 17 suitably hinged together as indicated at 18. The box 16 and cover 17 are preferably formed of metal, and are drawn to shape by well-known methods.

35 Mounted inside the enclosing structure 15, and supported by brackets 18 suitably secured to the box 16 and comprising a switch-supporting means, is a switch unit 20 of our invention. This switch unit is best illustrated in Fig. 1 and the 40 details thereof are illustrated in the subsequent figures. This unit comprises a panel 21 which is clamped to the brackets 19 by a pair of screws 22 and by a screw 23. The former screws fit into slots 25, while the latter bolt fits in a button-hole 45 socket 26 so that the whole switch unit may be quickly and easily removed from the supporting structure by loosening the screws 22 and 23 and raising this unit a small distance so that the heads of the bolts will not interfere with the direct 50 withdrawal of the switch unit from the enclosing structure. The panel 21 is preferably formed of molded insulating material, the type of material we prefer to utilize being that known in the art as "bakelite".

55 The switch unit 20 provides a mounting for four groups of switch elements. The main group of these elements is designated generally by the numeral 27 which is utilized as the main contact for supplying current to the electrical apparatus 60 controlled by the switch. The operation of the main switch elements 27 is governed by a magnetic means 28 controlled by a set of control switch elements indicated generally by the numeral 29.

65 We also provide interlock or auxiliary switch elements 30 which are utilized for maintaining the energization of the magnetic means 28 during the time that the switch is closed, as will be hereinafter explained. So also, the switch unit 20 70 provides relay switch elements 31 which are adapted to trip the switch upon the occurrence of certain predetermined adverse conditions.

Referring particularly to Figs. 1, 3, 4, 5, and 7 we have illustrated the main switch elements 27 75 as comprising three contacts 33, 34, and 35, each

of which is secured to the panel 21 by screws 36 threaded into sleeves 36a retained by the panel; and three contactors 37, 38, and 39 which are adapted to move into engagement with the contacts 33, 34, and 35 when the magnetic means 28 is energized in a manner to be hereinafter described. Inasmuch as the details of construction of each contact and contactor are identical only one pair of these elements and their associated structures will be described.

Thus, referring to these figures, we provide an arc shield 40 for each pair of main switch elements, this shield being preferably formed of a molded material having a high dielectric strength such, for instance, as that material known in the art as "bakelite". Each arc shield provides an apron which surrounds its pair of main switch elements on three sides, this apron being open at the rear end, and providing side walls 41 extending rearward into contact with the panel 21. 20 Each arc shield is held in place by a spring clip 43 retained by a screw 36 thereadjacent, in a manner best shown in Fig. 5. This clip is formed of a piece of spring metal bent into a U-shape illustrated in Fig. 5, the arms of the U being 25 normally spaced a distance greater than the distance between the walls 41 of the arc shield, so that when the arc shield is forced over the clip, these arms press outward against the side walls 41, thus acting to hold the arc shield in place. 30

The position of the arc shield on the panel 21 is determined by ribs 44 which are molded into the panel 21 and shaped as best illustrated in Fig. 3, these ribs being spaced apart a sufficient distance so that the side walls 41 of the arc shield fit 35 therebetween. These arc shields prevent arcs from forming between adjacent contacts or contactors, and the ease of removal of these arc shields is an important part of this invention inasmuch as it permits easy installation of the 40 switch. The removal of the arc shield permits direct access to screws 45 threaded into the contacts 33 to 35 and serve as a convenient means for making the electrical connections to these contacts. 45

All of the contactors 37, 38, and 39 are mounted on a contactor bar 46 formed of insulating material, these contactors being retained in channels 47 formed between adjacent barriers 48 which are formed integrally with the contactor 50 bar 46. Each contactor comprises a metallic bar, the lower end of which is pivoted to the contactor bar 46 by means of a pin 48a cast in place in the contactor bar 46, this pin extending into an opening 49 formed in the adjacent contactor. 55 As best shown in Figs. 4 and 7, the pin 48a is mounted in a projection 50 of the contactor bar 46, this projection having an arcuate front surface 51 on which the contactor pivots, the pin 48a acting to retain the contactor in place. The upper 60 end of each contactor provides a bent portion 52 which comes into engagement with the contact thereadjacent.

A resilient engagement between each contactor and its respective contact is maintained by a 65 spring 53, which is compressed between a head 54 of a key 55, and the contactor. The shape of the key is best shown in Fig. 6 and provides a lug 56 from which fingers 57 project. The key 55 is punched from a relatively thin sheet of metal, and the lug 56 passes through an opening 58 of the contactor and also through an opening 59 of the contactor bar. The openings 58 and 59 are elongated in a vertical plane to permit the passage of the fingers 57, but are too narrow in a 70 75

horizontal plane to permit this passage. Thus, by inserting the key through this opening and turning the key through 90°, the fingers 57 engage notches 60 formed at the rear end of the openings 59.

If the spring 53 is at this time in place, the key will be firmly locked, and can only be removed by forcing the head of the key toward the contactor, turning the key through 90°, and without drawing the key and its associated spring.

This contactor mounting is extremely simple in construction, and yet rugged enough to stand up under extremely severe conditions of operation. The pivotal connection between the contactors and the contactor bar is an important part of this invention, inasmuch as it insures line or surface contact between each contactor and its adjacent contact. Certain previous switches not using such a universal pivotal connection allow point contact to take place rather than line contact. Furthermore, while various methods of pivotally connecting the contactor to the contactor bar are possible and fall within the scope of this invention, nevertheless, we have found the particular one shown to be extremely simple and effective.

The contactor bar 46 is directly connected to an armature 63 which is formed of a plurality of laminations 64 bounded on either side by an armature side plate 65. These armature side plates have lugs 66 at the upper ends thereof, these lugs being bent sidewise and forming an attaching means for connecting the contactor bar to the armature. The lower ends of the armature side plates 65 extend rearward and terminate in toes 67, these rearward extending portions having circular openings 68 formed therethrough.

The axes of the openings 68 formed in both of the side plates 65 are in alignment and are adapted to form a pivotal connection between the armature 63 and a core 69, this connection being completed by any suitable pivot means such as a pivot pin 70 which passes through the openings 68.

The core 69 is formed of U-shaped core laminations 71 bounded by core side plates 72. These side plates extend below the U-shaped core and provide elongated openings 74 through which the pivot pin 70 passes, these openings being elongated in a horizontal plane. To provide an adjusting means permitting small adjustments of the contactor bar 46 and the armature 63 in an upright plane, we prefer to form the pivot pin 70 slightly smaller in diameter than the distance across the elongated openings 74. Similar openings 75 are formed a distance to the rear of the openings 74 and are adapted to receive screws 76 which are slidable therein, each of these screws being threaded into one end of a link 77, the other end of the link having a circular opening through which the pivot pin 70 passes. This structure provides an adjustable pivot means for pivoting the armature to the core, and is an important feature of this invention inasmuch as it permits the armature to be so adjusted with relation to the core as to eliminate the humming invariably present if the armature is not in surface contact with the upper leg of the U-shaped core. This upper leg is indicated by the numeral 78 and has a contacting surface 79 engaged by the armature.

The elongated openings 74 permit a relatively large forward and rearward adjustment of the lower end of the armature, and the independent attachment of the links 77 to the side plates 72

permits one end of the pin 70 to be moved more than the other if desired, thus pivoting the armature on an upright axis. Thus, this pivot means provides a universal adjustment of the armature to insure surface contact between the armature 63 and the contacting surface 79. When once properly adjusted the screws 76 may be tightened, thus clamping the link to the core side plate thereadjacent.

The extreme retracted position of the armature 63 is determined when the toes 67 of the armature side plates respectively contact an extrusion 72a formed on each core side plate 72.

The magnetic means 28 includes an electromagnet forming a holding coil 80 which is positioned around the leg 78 of the core 69 and is adapted to attract the armature 63 when energized. This holding coil is retained in place by a U-shaped retainer 81 which fits over the core and extends therewith through the holding coil 80. The forward ends of this retainer are bent sideward, as indicated by the numeral 82, to retain the holding coil in position relative to the core.

As will be noted from Figs. 3 and 7 in particular, the magnetic means is mounted in an opening 85 of the panel 21, the core 69 extending rearward into a wiring space 86 defined between a base 87 of the box 16 and the panel 21. Fig. 7 shows this relationship most clearly, this figure also illustrating knock-outs 88 which are formed in the walls of the box 16, preferably on all sides, so that when the cores thereof are knocked out, the remaining openings communicate directly with the wiring space 86.

Thus, conduits may be secured in place in any of the desired knock-out openings, as indicated by the dotted lines 89 of Fig. 7, and it is not necessary that the line wires and load wires extend from opposite sides of the switch as has been the case in previous structures. The provision of the wiring space 86 eliminates any wires in front of the switch unit and permits the switch unit to be completely wired even before positioning the switch unit in the enclosing structure if desired. Similarly, the switch unit may be removed from the enclosing structure without disturbing any of the wiring, the wiring space 86 acting as a storage space for a loop of wire in the event that a removal of more than a few inches is desired without disturbing the wiring of the unit.

Any particular mounting means may be utilized for mounting the magnetic means 28 in the opening 85, but we prefer to utilize a bracket 90 which is secured to the panel 21 by screws 90a and extends rearward and across the opening 85, this bracket being secured to lips 91 formed on the core side plates 72 and bent sidewise in the form of ears. If necessary washers may be placed around the screws 90a and between the panel and the bracket 90 to adjust the armature in a manner to insure that all of the contactors 37, 38, and 39 will simultaneously engage the contacts 33, 34, and 35.

The control switch elements 29 are positioned on a plate 95 formed of insulating material and having a pair of legs 96 contacting the panel 21 and retained thereagainst by screws 97. Positioned centrally on this plate is a metallic bracket 98 held thereagainst by screws 99 and 100 which pass through the plate and are threadedly received by the bracket.

A metallic plate 101 is similarly held in contact with that portion of the plate 95 to the left of the bracket 98 by means of screws 102 and 75

103. So also, a metallic plate 104 is retained in a similar manner by screws 105 and 106. A primary switch member 110 is slidably journaled in an opening 111 formed through the plate 95 between the screws 100 and 105 and through a boss 112 extending rearward from this plate. This switch member passes loosely through a disc 113, or other current-carrying member, which is adapted to short-circuit the forward ends of the screws 100 and 105 when the primary switch member 110 is depressed. As will be apparent from Figs. 8 to 10, this disc is resiliently retained between compression springs 114 and 115, the spring 114 being between the disc and a head of the primary switch member, while the spring 115 is between the disc and the lower end of an opening 116 formed concentric with the opening 111.

10 The screws 100 and 105 cooperate with the disc 113 in providing primary control switch elements which allow current to pass therethrough when a control member 120 is moved to the right. This control member is pivoted on a pin 121 retained in the bracket 98 and provides tabs 122 and 123 extending respectively to the right and to the left of the pin 121, the tab 122 being adapted to engage the head of the primary switch member 110 and move the primary control switch elements into engagement.

20 30 A portion of the control member 120 extends through an opening 124 of the cover 17 of the enclosing structure, this portion being termed an arm 125 and having at its outer end corrugations 126 to permit manual operation thereof. The opening 124 is formed in the rear wall of a cavity 126a of the cover 17, this cavity being preferably formed by a stamping operation. As will be noted from Fig. 7, the forward end of the arm 125 extends substantially in the same 35 40 plane as the cover 17, and thus does not extend substantially beyond the walls of the cavity 126a. This prevents any accidental contact with the control member, inasmuch as no part of this member extends forward of the enclosing 45 structure.

45 Adapted to be moved by the tab 123 when the control member is moved leftward, and slidably journaled in an opening 127 between the screws 99 and 102, is a secondary switch member 128 having a shoulder 129 formed at the junction of the body of this switch member and a reduced diameter portion 130.

50 55 A disc 131, or other current-carrying member, loosely surrounds the reduced diameter portion 130, and is adapted to short-circuit the screws 99 and 102 when the secondary switch member 128 is not being depressed by the control member 120. This engagement is made possible by a spring 132 compressed between the disc 131 and a cotter pin 133 extending through the reduced diameter portion 130. Another spring 134 is compressed between the plate 95 and a head formed on the secondary switch member 128.

60 65 70 The springs 114 and 115 are so designed that they hold the disc 113 in a position shown in Fig. 8 under normal conditions, and the springs 132 and 134 are so designed that they hold the disc in contact with the screws 99 and 102 under such conditions. Similarly, these springs are designed to return the control member to a central position after manual engagement therewith has ceased.

75 The details of the relay switch elements 31 are best illustrated in Figs. 1, 3, 7, and 8 to 10.

Referring to these figures, we provide relay contact springs 135 and 136 extending in channels formed in the face of the panel 21, these channels meeting in the form of a V, as best shown in Fig. 3, the relay contact springs 135 and 136 being retained therein by screws 137. The adjacent ends of these contact springs overlap and provide contacts which normally tend to separate, but which are held in engagement by a latch 140 pivoted in a bracket 141 retained in a channel of the panel 21. This latch member is pivoted on a pin 142 and is moved by a spring 143 in such a direction that a tooth 144 thereof normally retains the contact spring 135 in engagement with the contact spring 136.

screw 105 is connected to another of the conductors of the supply line by a conductor 169 so that if the control arm 120 is moved to the right in a manner to close the primary control switch elements, as indicated in Fig. 9, the holding coil, the relay contacts, and the primary and secondary control switch elements will be in series with each other across one phase of the supply line.

with the primary control switch contacts. Similarly, a high pressure cut-out or other protective device may be adapted to actuate a switch 187 connected between the screws 102 and 103, the bridging plate 101 being removed. Such protective devices are well known in the art and need not be specifically described, the function of this protecting device being to open the switch 187 upon the occurrence of a predetermined adverse condition. Such a protective device may act as a function of excessive pressure, low water level, low voltage, etc.

Thus, with the control element in neutral position, and the switch of the high pressure cut, or similar device closed, the holding coil 80 is energized whenever the contacts of the thermostatic, or other control switch, close, and is de-energized whenever these contacts open, thus providing automatic control governed by the control switch 185. If, however, manual control is to be resumed, the control member 120 is thrown to the right and is retained by the clip 180 in the position shown in Fig. 9, thus short-circuiting the control switch and continuously energizing the load until such a time as the contacts of the high-pressure cut-out or similar device open, which would, of course, de-energize the holding coil 80.

It should be understood that we are not limited to the particular form of the elements shown although the particular combination of elements illustrated has proved very effective. Various modifications may be made without departing from the spirit of the invention and we desire our invention to be limited only by the appended claims taken in conjunction with this disclosure and interpreted in their broadest scope.

We claim as our invention:

1. In a switch device of the character described, the combination of: a supporting structure; primary switch means supported by said supporting structure; secondary switch means supported by said supporting structure; a reset relay switch means supported by said supporting structure; a control member movably mounted on said supporting structure to separately operate said primary and secondary switch means and to operate said reset relay switch simultaneously with one of said primary or secondary switch means, and resilient means urging said control member into position in which it operates none of said switch means.

2. In a switch construction, the combination of: an enclosing structure; switch means mounted in said enclosing structure; a swingable control lever for controlling the operation of said switch means having a position in which said switch means is opened and another in which said switch means is closed; and a cover for said enclosing structure, having a depression with an opening therein through which said control lever extends so as to be operable from the exterior of said enclosing structure and cover while not protruding beyond the face of said cover, said control lever having a portion which fills said opening at all positions of said control lever. 60

3. In a switch construction, the combination of: an enclosing structure; switch means mounted in said enclosing structure; a swingable control lever for controlling the operation of said switch means having a position in which said switch means is opened and another in which said switch means is closed; and a cover for said enclosing structure, having an elongated opening through which said control lever extends so as to be op- 70 75

erable from the exterior of said enclosing structure and cover, said control lever having a segment-shaped portion which fills said opening at all positions of said control lever.

5. In combination: a plate; primary and secondary switch members movable relative to said plate; primary and secondary switch elements respectively actuated by a movement of said primary and secondary switch members; a control member mounted in pivoting relationship with said plate in a manner to engage said primary switch member when moved in a primary direction and to engage said secondary switch member when moved in a secondary direction; and resilient means urging said primary switch member for actuating said primary switch element to circuit closing position and urging said secondary switch member for actuating said secondary switch element to circuit opening position, said resilient means urging said control member into neutral position.
10. In combination: a plate; primary and secondary switch members movable relative to said plate; primary and secondary switch elements movable into circuit closing and circuit opening positions in response to movement of said switch members; a control member mounted in pivoting relationship with said plate in a manner to actuate said primary switch member when moved in a primary direction and to actuate said secondary switch member when moved in a secondary direction; and resilient means associated with each of said switch elements for permitting further movement of either of said switch members and further movement of said control member in a direction to actuate said either of said switch members to circuit closing position after said switch element associated with said either of said switch members is in circuit closing position.
15. In combination: a plate; primary and secondary switch members movable relative to said plate; primary and secondary switch elements respectively actuated by a movement of said primary and secondary switch members; a control member mounted in pivoting relationship with said plate in a manner to engage said primary switch member when moved in a primary direction and to engage said secondary switch member when moved in a secondary direction; resilient means urging said primary switch member for ac-

tuating said primary switch element to circuit closing position and urging said secondary switch member for actuating said secondary switch element to circuit opening position, said resilient means urging said control member into neutral position; and other resilient means between each of said switch members and its companion switch element for resiliently resisting further movement of said switch member after its companion switch element is in circuit closing position.

10. In combination: a plate; primary and secondary switch members movable relative to said plate; primary and secondary switch elements movable into circuit closing and circuit opening positions in response to movement of said switch members; a control member mounted in pivoting relationship with said plate in a manner to actuate said primary switch member when moved in a primary direction and to actuate said secondary switch member when moved in a secondary direction; and resilient means associated with each of said switch elements for permitting further movement of either of said switch members and further movement of said control member in a direction to actuate said either of said switch members to circuit closing position after said switch element associated with said either of said switch members is in circuit closing position.
